UNITED STATES PATENT OFFICE

2,599,304

FLUID PRESSURE DISCHARGE APPARATUS

Carl Weber, New York, N. Y., assignor to The Prehy Company, Incorporated, New York, N. Y., a corporation of New York

Application August 24, 1946, Serial No. 692,912

2 Claims. (Cl. 302—56)

1

This invention relates to apparatus for discharging comminuted material from storage tanks through pneumatic material conveyors and refers more particularly to an apparatus adapted for uniformly and accurately adjusting the dispersion of dry or wet granulated or finely powdered materials from pressure tanks into conveyor conduits from which the material is discharged by a fluid current.

The invention comprehends an apparatus of the indicated character which is particularly adapted for the transportation and distribution of comminuted materials such as fertilizers, insecticides, dry chemicals for fire fighting apparatus, materials for mortar blowing and sand blasting machinery and for the transportation and distribution of other similar materials for which the apparatus possesses economic and technical advantages.

The efficiency of apparatus for discharging comminuted materials is largely dependent upon correct and uniform dispersion of the material into the transporting fluid current which carries the finely divided particles thereof in suspension through the conveyor conduit and ejects the same therefrom at the point of destination or use with the required velocity.

The invention has for a further object the provision of an apparatus of the indicated character which is adjustable to provide for the correct and uniform dispersion of the material and to instantly vary the supply of the material to meet the required volume thereof at the point of discharge and which is adjustable to compensate for variations in moisture content and gravity of the material and fluctuations in the working pressure of the fluid in order to avoid irregular pulsating or puffing discharge of the material and waste of power by interruptions of the work at the point of application due to filling up or plugging of the conveyor conduit.

The present invention also has in view the provision of an apparatus of said character which permits of adjustment for the handling of different characters of material such as heavier or bulkier material, coarsely comminuted material, wet or sticky material or quick hardening material for use in mortar blowing and sand blasting machines and the like. As such apparatus are generally operated in the open where the same and the material are exposed to varying weather conditions, atmospheric variations of humidity and temperature causing fluctuations in the weight and consistency of the material adjustments must be made in the operation thereof.

2

to vary the rate of material supply in order to maintain the required service efficiency.

In apparatus in common use for the continuous discharge of material from a supply tank into a conveyor conduit, a heavy cast-iron conical shaped dispersing wheel is employed having a series of radially disposed fins projecting outwardly from the wheel and open at the top and ends in which the material is carried by rotation into intercepting relation with the fluid current directed through one of the pockets thereof and through a hairpin turn so as to carry the material into the conveyor conduit in an angulated direction of flow. Such heavy dispersing wheel has the disadvantage that the same requires a considerable amount of power to effect rotation thereof which is increased by the frictional resistance of hard material deposits that accumulate in the clearance spaces at the periphery of the rim of the wheel and below the wheel and due to the fact that water or slightly moist material such as sand, mortar and the like quickly form encrustations in the wheel pockets which greatly reduce the working capacity of the apparatus, the apparatus can only be used with dry comminuted materials or compounds without frequent interruptions for the removal of such deposits which cause costly delay in the operation. Furthermore, the necessity of using dry material causes excessive loss of materials by segregation and dusting and the frequent formation of sand pockets and laminated mortar deposit on the wheel and inside surface of the supply tank which is an objectionable feature of such apparatus for use in the handling of materials for mortar blowers. A further objection to such apparatus is the fact that the fluid current is conducted through a bend of approximately 180 degrees in dispersing the material from the pocket into the discharge line. The centrifugal force created by the bend causes moisture in the fluid current to be thrown into the pocket between the fins and onto the surfaces of the wheel resulting in the formation of hardened encrustation thereon which necessitates costly interruption of the operation of the machine for the removal thereof. In order to overcome such objection air dryers or water separators have been employed for extracting moisture from the fluid current but the use of such additional apparatus renders installation complicated and adds to the expense and cost of operation.

In order to overcome these objections the present invention has in view the provision of an apparatus for dispersion of material from the

supply tank into the conveyor conduit by means of a relatively light-weight rotating ring provided with radially disposed depending blades for conveying the material in intercepting relation with a fluid current which passes radially through the apparatus in parallel relation with the fins and in alignment with the conveying conduit to effect a complete dispersion of all the materials conveyed by the blades and a complete cleaning of each blade in turn to thereby eliminate the formation of encrustation and pockets of the material and which permits of the use of wet or moist material as well as dry comminuted material.

With the foregoing and other objects in view, reference is now made to the following specification and accompanying drawings in which the preferred embodiment thereof is illustrated.

In the drawings:

Fig. 1 is a vertical sectional view through a pressure tank provided with a discharge apparatus constructed in accordance with the invention and illustrating parts in full.

Fig. 2 is a fragmentary vertical sectional view of the pressure tank with the closure in open relation.

Fig. 3 is a horizontal sectional view taken approximately on line 3—3 of Fig. 1.

Fig. 4 is a fragmentary vertical sectional view taken approximately on line 4—4 of Fig. 3 and showing the reduction gearing.

Referring to the drawings by characters of reference, the apparatus includes a supply tank 10 adapted to receive comminuted or plastic material for discharge therefrom by means of a discharge device 11 into a tubular conduit 12 for conveyance to the place of use. The tank 10 is of any preferred construction or formation having a filling opening 13 at the top thereof surrounded by a funnel shaped hopper 14 and adapted to be closed by a ball valve 15 pivoted for downwardly swinging opening movement.

The discharge device 11 consists of a conical shaped base 16 provided with a central depending tubular extension 17 formed integrally with the upper end thereof and secured in vertical relation at its lower end in the centrally apertured bottom wall 19 of the tank 10 with the outer periphery of the conical shaped base 16 supported upon the upper surface of the bottom wall so as to provide an outwardly and downwardly inclined surface for gravitationally feeding the material outwardly in surrounding relation with the base and between the same and the cylindrical wall of the tank.

Mounted for rotation upon the conical shaped bases 16 is a rotor 20 consisting of a ring 21 secured to the outer ends of radially projecting arms 22 which are formed integral with and radiate from a common hub 23 secured by a nut 24 upon the upper end of a vertical shaft 25 journaled in the tubular extension 17 and connected at its protruding lower end with suitable reduction gearing 26 located in a casing 27 affixed to the under side of the bottom wall 19 of the tank. The hub 23 is supported upon the upper horizontal face of the base 16 with the arms 22 extending downwardly and outwardly therefrom in inclined overlying relation with the upper surface of the base and with the outer ends thereof extending horizontally outward so as to support the ring 21 above the bottom wall 19 of the tank and approximately midway between the bottom of the base 16 and the cylindrical wall of the tank 10.

Secured to the ring 21 and depending from

the under side thereof are a plurality of radially disposed vertical fins 28 which extend into the annular space or trough surrounding the base 16. The fins 28 are formed with vertical outer edges, horizontal bottom edges and inclined inner edges so as to conform with and have wiping engagement with the cylindrical wall of the tank, the bottom wall thereof and the inclined surface of the base 16 forming the said trough.

10 The material is discharged from the tank by a fluid current such as steam or compressed air which is under pressure to disperse the material and carries the same through the conduit 12 in a state of suspension in the fluid. The fluid current is conducted from a source of supply through a suitable pipeline 30 which extends into the tank through the bottom wall 19 thereof with the outlet end 31 opening radially through an aperture in the base 16 adjacent the bottom thereof. The conduit 12 is secured to the side wall of the tank 10 with the discharge opening 32 disposed in radial alignment with the fluid current outlet 31 and in parallel relation with the lengths of the fins 28 as the same pass between the said outlet and discharge opening.

15 In order to provide for uniformity of material supply and to discontinue the supply when the rotor is at rest, a cover plate 33 is provided which is secured to the cylindrical wall of the tank 30 above the discharge outlet 32 and extends horizontally inward above the fluid stream with the inner edge thereof terminating in narrow spaced relation from the base 16. The arms 22 have outwardly extending horizontal bars 34 secured thereto which are located so as to pass over the upper surface of the plate 33 for removing the material therefrom so as to prevent the accumulation or compaction of the same thereon.

20 The material in the tank 10 is subjected to static pressure upon the top thereof which is admitted thereto by a pipeline 35 connected with the pipeline 30 and having a valve 36 for regulating the pressure within the tank. A throttle valve 37 is provided in the pipeline 30 for regulating the volume of fluid current admitted through the outlet opening 31. The rotor 20 is driven through the reduction gearing 26 by means of a drive shaft 38 connected with a motor 39 operated by fluid current admitted thereto through 25 the branch pipe 40 connected with the pipeline 30 and having a valve 41 interposed in the branch pipeline 40 for controlling the speed of the rotor.

25 It will be understood that the fluid current striking the material brought into the intercepting relation therewith at right angles to the direction of rotation of the fins results in a complete removal of the material from the trough as the material is brought into alignment with the discharge outlet 31. The material is also completely removed from the fins so as to prevent the formation of hardened encrustations which cause excessive friction and reduce the working efficiency of the apparatus regardless of the water suspension in the fluid current or the moisture content of the material. There is thus provided a discharge apparatus which can be instantly adjusted to control the speed of the rotor and the volume and pressure of the fluid current so as to provide a constant and uniform supply of the material at the place of use.

30 What is claimed is:

35 1. In apparatus for discharging comminuted material from a pressure supply tank by fluid pressure, a discharge device in the bottom of the tank which comprises a stationary conical-shaped

base spaced from the side wall of the tank so as to provide an annular trough surrounding the base, a discharge conduit from the annular trough in the wall of the tank, an outlet in the conical-shaped base in horizontal alignment with the discharge conduit, a fluid pressure pipe line to the outlet in the base, a light-weight replaceable rotor mounted for rotation upon the base and consisting of arms movable over the conical-shaped face thereof, a ring secured to said arms and a plurality of radially arranged fins depending from said ring and movable in the trough with the movement of the rotor for moving the material in the tank about the base for discharge.

2. In apparatus for discharging comminuted material from a pressure supply tank by fluid pressure, a discharge device in the bottom of the tank which comprises a stationary conical-shaped base spaced from the side wall of the tank so as to provide an annular trough surrounding the base, a discharge conduit from the annular trough in the wall of the tank, an outlet in the conical-shaped base in horizontal alignment with the discharge conduit, a fluid pressure pipe line to the outlet in the base, a light-weight replace-

15

5

able rotor mounted for rotation upon the base and consisting of arms movable over the conical-shaped face thereof, a ring secured to said arms and a plurality of radially arranged fins movable in the trough for moving the material in the tank about the base for discharge, a plate disposed above the opening of the discharge conduit for preventing downward flow of the material into the path of the fluid pressure medium and bars carried by the arms of the rotor for movement over the plate for preventing accumulation of the material theron.
